United States Patent

Des. 235,682
Patented July 1, 1975

235,682

CONTROL HOUSING FOR A RADIO

David L. Haas, Norwalk, Conn., assignor to
General Electric Company

Filed June 25, 1973, Ser. No. 373,404

Term of patent 14 years

Int. Cl. D14—03

U.S. Cl. D56—4 B

FIG.1

FIG.2

FIG.3

FIG.4

FIG.5

FIG. 1 is a front, top and left side perspective view of a control housing for a radio showing my new design;

FIG. 2 is a top plan view;

FIG. 3 is a front elevational view;

FIG. 4 is a left side elevational view; and

FIG. 5 is a right side elevational view.

The rear of the housing is plain and unornamented.

I claim:

The ornamental design for a control housing for a radio, as shown, and described.
